UNITED STATES PATENT OFFICE

98,279

DESIGN FOR A MATCH BOX

Carl W. Sundberg, Detroit, Mich., assignor to Erie Resistor Corporation, Erie, Pa., a corporation of Pennsylvania

Application November 16, 1935, Serial No. 59,612

Term of patent 7 years

To all whom it may concern:

Be it known that I, Carl W. Sundberg, a citizen of the United States, residing at Detroit, in the county of Wayne and State of Michigan, have invented a new, original, and ornamental Design for a Match Box, of which the following is a specification, reference being had to the accompanying drawing, wherein:

Fig. 1 shows a side elevation of one side of a box showing my new design.

Fig. 2 shows an end view.

Fig. 3 shows a side elevation of the reverse side of the box.

Fig. 4 is a perspective view showing the box in open position.

I claim:

The ornamental design for a match box as shown and described.

CARL W. SUNDBERG.
